United States Patent Office

Des. 185,277
Patented May 26, 1959

185,277

EAR MUFF

Doris Fleischer, New York, N.Y.

Application May 12, 1958, Serial No. 50,844

Term of patent 7 years

(Cl. D3—2)

FIG.2

Fig. 1 is a front elevational view of an ear muff showing my new design; and

Fig. 2 is a side view thereof, the side opposite thereto being similar in appearance.

I claim:

The ornamental design for an ear muff, substantially as shown and described.
